UNITED STATES PATENT OFFICE.

PETER A. BECH, OF BROOKLYN, NEW YORK.

KNEE-REST.

1,170,396.

Specification of Letters Patent.

Patented Feb. 1, 1916.

Application filed May 16, 1913. Serial No. 768,148.

To all whom it may concern:

Be it known that I, PETER A. BECH, a subject of the King of Norway, residing at Brooklyn, in the county of Kings and State 5 of New York, have invented new and useful Improvements in Knee-Rests, of which the following is a specification.

The general object of the invention is to provide a yielding support for the knees; 10 especially adapted to relieve the strain on the knees of those who work in a kneeling position and who must necessarily kneel upon a firm support, such as hard-wood or stone. And to these ends the invention consists of a bearing portion and a yielding 15 support for the knees positioned above the bearing portion and being in spaced relation therewith.

Other objects will appear and be better 20 understood from that embodiment of my invention of which the following is a specification, reference being had to the accompanying drawings forming part hereof, in which:—

25 Figure 1 is a perspective view of the device in its operative position. Fig. 2 is a side elevational view of the device in its folded position.

The knee rest generally designated by a 30 consists of a base plate 5, uprights 6 and 7 and a supporting strap 8. Grooves 9 and 10 are provided on the upper face 11 of the base and serve as sockets for the rounded ends 14 of the uprights. These rounded 35 ends are provided to facilitate, in conjunction with the grooves, the positioning of the uprights, upon unfolding the device.

Strips 12 and 13 are mounted on the under face of the base plate 5 and are in 40 alignment with the uprights 6 and 7. These strips are by preference, made of rubber, and are provided to decrease the area of contact between the base and the floor, and so prevent defacement of floors, such as 45 polished hardwood.

The strap 8 may be made of any suitable material such as canvas, and has its ends carried over and fastened to the under side of the base, as shown at 15. The strap is

also secured to one end of uprights 6 and 7 50 by means of the batten strips 16 and 17.

The truss-like arrangement of the parts as shown in Fig. 1, presents a substantial but relatively elastic support for the knees. It will be seen that upon weight being applied 55 to the strap 8, the uprights will vary from the perpendicular, and the horizontal distance between the upper ends of the uprights will be less than that between the lower ends. This movement is permitted 60 by means of the uprights being mounted in the grooves 9 and 10 so that they are free to turn. As this movement occurs the parts 18 of the strap will be tautened and upon the weight being released from the strap 65 the tendency of the parts 18 will be to return to their normal positions the uprights 6 and 7.

What is claimed as new is:

1. A kneeling rest comprising a base, a 70 pliable strap, connected at its ends with the ends of the base and being longer than the base, and relatively rigid uprights attached to the strap at points between the ends thereof and adapted to be interposed on edge 75 between the base and the strap to hold the intermediate portion of the strap spaced from the intermediate portion of the base.

2. A kneeling rest comprising a base provided at one side with grooves, a pliable 80 strap connected at its ends with the ends of the base and being longer than the base, transversely disposed strips located at the other side of the base and opposite the grooves, and relatively rigid uprights 85 attached to the strap at points between the ends thereof and adapted to be interposed on edge in said grooves and between the base and the strap to hold the intermediate 90 portion of the strap spaced from the intermediate portion of the base.

In testimony whereof I affix my signature in presence of two witnesses.

PETER A. BECH.
